(57) **CLAIM**

I claim the ornamental design for a guitar slide storage, as shown and described.

DESCRIPTION

FIG. 1 is a top perspective view of a guitar slide storage of a storage case, wherein a lid thereof is in an open position. FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a top plan view thereof.

FIG. 7 is a bottom plan view thereof; and,

FIG. 8 is a top plan view of the guitar slide storage, wherein the lid is in a closed position, and wherein a cap opening of the lid is removed for visibility of the guitar slide storage through the lid.

Those features shown in broken lines form no part of the claimed design.
